PRINTING INSTRUMENTALITY FOR
TYPEWRITING MACHINES

Frank H. Trego, New York, N. Y., assignor, by
mesne assignments, to Ralph C. Coxhead Cor-
poration, New York, N. Y., a corporation of
Delaware

Application March 24, 1931, Serial No. 524,816

12 Claims. (Cl. 197—49)

This invention relates to typewriting machines and more particularly to printing instrumentalities therefor.

The invention is shown as applied to the Vari-type writing machine, which machine includes a type carrier operable about an axis, by means including an actuator, under the control of key levers, to locate a selected one of a plurality of types at the printing point. Indexing devices are settable by the key levers and are engaged by the actuator to register the selected type at the printing point. A hammer is then operated to co-operate with the type carrier and thus print on an interposed work sheet.

15 The present invention is in the nature of improvements which may be used with some of the devices disclosed in my application, Serial No. 495,872, filed Nov. 15, 1930 and in which the hammer is operated by an electro-magnet, under 20 the control of the key levers, to facilitate the operation of the machine.

An object of this invention, in which the hammer is also actuated by an electro-magnet, is to prevent premature actuation of the hammer; or, 25 in other words, to insure against operation of the hammer before the selected type of the type carrier or shuttle reaches the printing point.

To this end there is provided a normally open switch which is electrically connected with the 30 electro-magnet. Said switch, in the present form of the invention, is carried by the shuttle and is operated by the active one of the indexing devices as said actuator approaches the latter.

35 Provision is made to render the electro-magnet ineffective so that the hammer may be restored to normal without delay which may otherwise be caused by holding closed the switch associated with the shuttle actuator. For this purpose there is provided a normally closed switch in the electric circuit of the electro-magnet. The operation of said switch, to open it, is started by the hammer, and is delayed and then completed by suitable means, so as to prevent a premature 40 return of the hammer, and to insure immediate return of the hammer after printing.

45 Other features and advantages will herein-after appear.

In the accompanying drawings,

50 Fig. 1 is a sectional side view of the machine; Fig. 2 is a top plan view of a portion of the machine showing the shuttle actuator and its associated parts in normal position.

55 Fig. 3 is a view similar to Fig. 2 showing the type shuttle actuated and the switch, associated

with the shuttle actuator, operated by the latter and the indexing device.

Fig. 4 is a detail, vertical section, on an enlarged scale, illustrating the type shuttle actuator and the associated switch.

Fig. 5 is a rear view of the carriage escapement mechanism and the switch associated therewith.

Fig. 6 is a diagrammatic view of the electric circuit.

Fig. 7 is a diagrammatic view of a modified 10 electric circuit.

Similar reference characters represent similar parts throughout the various views.

The machine includes a main frame 15 having thereon a track 16 upon which is supported a 15 carriage 17 to travel back and forth through the medium of anti-friction balls or rollers 18, said carriage being urged in a letter space direction by the usual spring drum, not shown, to which it is connected by a strap 19. The carriage is 20 provided with feed rollers 20 and 21 by which a work-sheet 22 may be fed upwardly between a type carrier or shuttle 23 and a hammer 24, the latter being located behind the work-sheet.

The type shuttle 23, which is located in front 25 of the work sheet, is supported on an anvil 25 secured to a shaft 25a suitably supported by a cross-bar 26 and a plate 27 on the machine frame 15. The type shuttle is operable by an actuator 30 or lever 28 connected to said shuttle by an upwardly extending finger 29 engaging a fin 30 which extends through a slot 31, in the anvil 24, the fin serving also to support the shuttle on the anvil.

The shuttle actuating lever 28 is secured to a 35 sleeve 32 rotatable about the shaft 25 and resting on the cross-bar 26. The shuttle actuator 28 may be operated in a clockwise and a counter-clockwise direction (Fig. 2), from a central position, in a manner described in the above mentioned application, or in the usual manner by means of two universal bars 33, only one being illustrated. Key levers 34 are divided into two groups, one group at each side of the middle of the machine; each group being associated with 45 one of the universal bars. Upon the depression of any one of the key levers 34, about its fulcrum 34a the rear end thereof engages the universal bar 23 to swing it upwardly about a shaft 35. Each universal bar has an upwardly extending arm 36, the free end of which engages the actuator 28 to operate the latter to actuate the type shuttle.

To accurately register the selected types of 50 said shuttle at the printing point, indexing de- 55

vinces or stops 40 are provided, one associated with each key-lever 34, each being operable, by its key lever, against the action of a return spring 41, to project the upper end into the path of an arm 42 of the shuttle actuator 28.

The carriage 17 is connected by the usual rack 45 with a pinion 46 of the carriage escapement 47 which is actuatable by a universal bar 49 engaged by the rear end of the key levers 34. The universal bar 49 rocks a shaft 50 having secured thereto a rearwardly extending arm 51 which operates a dog-rocker 52 about its pivot 53 (Fig. 5) to carry a fixed dog 54 into the path of the teeth 55 of an escapement wheel 56 secured to a shaft 57, the escapement wheel having the usual one-way driving connection including a spring-pressed pawl 58, on a disk 59 secured to the pinion 46 which is loosely supported on the shaft 57. The one-way driving connection further includes a ratchet 60, connected to the shaft 57, and engaged by the pawl 58.

After the dog 54 has entered the path of the teeth of said escapement wheel a loose dog 61 is swung, about its pivot 62, out of engagement with the escapement wheel, by an arm 63 of the dog rocker 52, said arm being provided with a slot 64 into which extends a pin 165 from said loose dog. Upon the release of the loose dog from the escapement wheel, it is carried upwardly by a frame 66 pivotally supported on the escapement shaft 57, said frame being actuated by the printing hammer through the connecting pin 67, the hammer being operated, to print, in a manner hereinafter described. The dog 61, as it is carried upwardly, is guided into the path of the next adjacent tooth of the escapement wheel by the inclined slot 64 so that upon the release of the escapement wheel from the dog 54 the escapement wheel, by its movement, returns the loose dog to normal, thus completing the letter feeding movement of the carriage.

The means to actuate the printing hammer 24 includes a solenoid 70 (Fig. 1) which is connected in circuit with a source of power 72 (Fig. 6), a conductor 73, a hand switch 74, a conductor 75, a normally open switch 75^a, a normally closed switch 76 and a conductor 77. The electric circuit further includes a conductor 78, a contact segment 79, a switch 80 associated with the type shuttle actuator 28, a conductor 81 and ground 82, which may be the main frame of the machine.

The solenoid 70 is energized by the actuation of any one of the key levers, in a manner hereinafter described, to draw the plunger 85 into the coil 86 of said solenoid, to actuate the hammer 24 about the axis of a shaft 87, the plunger being connected to the hammer 24 through the medium of a link 88 connected to a downwardly extending arm 89 secured to the hammer 24. After the printing operation the solenoid is de-energized, in a manner hereinafter described, and the hammer is subsequently restored to normal by a spring 90 connected to the hammer arm 89.

To energize the solenoid 70 the circuit is first conditioned by closing the switch 75^a by the actuation of any one of the key levers 34, which key levers, it will be remembered, actuate the dog rocker 52 in a clockwise direction (Fig. 5), through the medium of the universal bar 49 and the arm 51. The dog rocker carries a movable contact 92, of the switch 75^a, into engagement with a fixed contact 93 to close said switch 75^a; this operation preceding the closing of the switch 75 80.

The completion of the circuit closing operation takes place during the latter part of the actuation of the type shuttle, irrespective of the angular distance traveled by the latter. For this purpose the switch 80 is carried by the shuttle actuator 28 (Figs. 1, 2 and 4), and comprises two contact elements 95 and 96, the element 95 being secured to the actuator 28 by a bolt 97; said contact element and bolt being suitably insulated from the actuator by washers 98 and a sleeve 99 10 of insulating material.

The other contact element is secured to a headed stud 100 pivotally supported on the actuator 28; the upper end of the stud having secured thereto a collar 101 from which extends a flat 15 spring 102 engaging between two projections 103 of the actuator to hold the pivoted switch element 96 in a central position with reference to the actuator 28.

During the initial part of the operation of the 20 actuator 28, in either direction from its normal position in Fig. 2, there is no motion of the switch element 96 about its pivot. As soon as said switch element reaches the actuated one of the indexing devices 40 it is obstructed thereby 25 and a further movement of the actuator 28, until it also reaches the set indexing device (Fig. 3), causes the switch element or lever 96 to be actuated about the axis of the stud 100, against the action of the spring 102, to carry a contact 104, 30 of the switch element 96, into engagement with a contact 105, of the fixed, switch element 95, thus closing the circuit to energize the solenoid 70 and thereby actuate the printing hammer 24 as previously described. The element or lever 35 96 and the spring 102 also tend to push the lever 28 away from the effective indexing pin to hasten the return of the shuttle lever 28, thus expediting the operation of the machine. It will be understood when the shuttle actuator moves clockwise 40 from its central position in Fig. 2 that the switch 80 is closed by contacts 106 and 107.

Electrical connection is maintained between the movable switch 80 and the fixed conductor 78 by a head 108, on the bolt 97, which has sliding contact with the contact segment 79 to engage it in all positions of the actuator 28; said segment being connected to the conductor 78 and being insulated from the machine frame by a block 109 of insulating material. 50

The switch 76 includes a fixed contact 115 on a block 116 of insulating material (Figs. 1, 5 and 6) mounted on a bracket 117 secured to the main frame 18, the contact 115 being connected to the contact 93 of the previously described switch 75^a, 55 by a conductor 118. Co-operating with the contact 115 is another contact 119 supported on a bell-crank lever 120 pivoted by a screw or stud 121 on the bracket 117. A detent spring 122 secured to the bracket 117, acts through the medium 60 of a roller 123 on one side of a nose 124 of the bell crank lever 120 to hold the switch closed as in Fig. 5.

The operation of the switch 76 is initiated by the hammer during its actuation to the printing 65 point, through the medium of the dog carrying frame 66; the frame 66 being provided with a lug 125 which engages a finger 126 of the switch lever 120 to swing the latter about its pivot 62 in a clockwise direction (Fig. 5) until the point of 70 the nose 124 wipes past the roller 123, of the detent 122, the switch 76 remaining closed although the switch lever 120 has been partially actuated; the contact 119 being slidably supported for this purpose on the switch lever 120 75.

and being urged toward the contact 115 by a spring (not shown). The contact 119 is supported in a block 127 of insulating material which is suitably attached to the switch lever 120.

5 It should be understood that the printing of the hammer has taken place when the switch 16 is partially operated as above described and the switch is still closed. Instantly after printing, however, the spring 122 acts to complete the operation of the switch lever 120 to open the switch 16 to break the circuit and thus de-energize the solenoid to permit the return of the hammer 24.

Upon the return of the hammer to normal the dog carrying frame 66 is returned therewith and the lug 125 engages a finger 128 of the switch lever 120 to start its return stroke, which return stroke is completed by the spring 122 to close the switch 16. Before the closing of the switch 16 is effected, however, the switch 75^a is opened by 20 the return of the dog rocker 52 to normal.

25 It should be understood that it is a feature of the normally open switch 75^a, in the circuit, to guard against actuation of the hammer by an accidental closing of the switch 80 associated with the shuttle actuator 28, or, in other words, to insure against operation of the hammer 24 except when a key lever is operated.

30 Due to the fact that the source of energy 12 and the conductor 80 are grounded on the machine frame 15, it is advantageous to employ the switch 75^a in the circuit, because it provides a means to prevent a shock to the operator while the machine is at rest and the power switch 74 is closed.

35 In a simplified form of the invention the switches 75^a and 16 may be excluded from the circuit as indicated in Fig. 7 where the conductor 75 is connected directly to the solenoid 70. It will be understood that in this form of the invention care must be exercised to remove the fingers from the key levers as quickly as possible so as to prevent heating of the solenoid coil 86 and so as not to retard the operation of the machine. In this arrangement, however, grounding the source of energy 12 and the conductor 80 on the machine frame is avoided; the conductor 80 being connected directly with the source of energy.

40 While certain preferred embodiments of the invention have been shown and described, it will be understood that changes in the form, arrangement, proportions, sizes and details thereof may be made without departing from the scope of the invention as defined in the appended claims.

45 I claim:—

1. In a typewriting machine, the combination of printing instrumentalities including a type carrier, and a co-operative element, means to operate the cooperative element means to actuate the type carrier, key levers to operate the actuating means, means operable by the key levers while operating the actuating means to prepare the first mentioned means for a subsequent actuation, and a device associated with the preparing means and operable by the actuating means for the type carrier to effect the actuation of the first-mentioned means to thus actuate the co-operative element.

2. In a typewriting machine, the combination of printing instrumentalities including a type carrier, and a co-operative element, means to actuate the type carrier, means to locate the type carrier with respect to the co-operating element, electric means to actuate the co-operative element, means associated with the locating means

to effect the actuation of the electric means, and means to render the electric means ineffective after the printing operation while the associated means is still actuated.

3. In a typewriting machine, the combination of printing instrumentalities including a type carrier, and a co-operative element, a fixed anvil to support the type carrier, a rod to support said anvil, an operating lever pivoted to swing about said rod and actuatable in opposite directions thereon to actuate the type carrier, means including key levers to actuate said operating lever, indexing devices with which said operating lever co-operates to register the selected type at the printing point, an electro-magnet to actuate the co-operative element, and a normally open switch electrically connected with said electro-magnet, said switch including a fixed contact element and a pivoted contact element normally in a central position and adapted to swing in opposite directions to either of two effective positions, both of the switch elements being supported on the actuating lever, the pivoted contact element being carried bodily with the actuating lever when the latter is operated, said pivoted element being operated about its pivot by the active indexing device as the actuating lever approaches it to cause said pivoted element to engage the fixed element and thus render the electro-magnet effective.

4. In a typewriting machine, the combination of printing instrumentalities including a type carrier, and a co-operative element, an actuator for the type carrier, key levers, means actuatable by the key levers to operate said actuator, an electro-magnet to operate the co-operative element, means operable by the key levers to set up a condition affecting the electro-magnet for future operation, means operable by said actuator while the operable means is in its active position to effect the operation of the electro-magnet, means to render the electromagnet ineffective after it has operated said co-operative element, and means operable by the key levers to effect actuation of the last mentioned means.

5. In a typewriting machine, the combination of printing instrumentalities including a type carrier, and a co-operative element, an actuator for the type carrier, key levers, means actuatable by the key levers to operate said actuator, an electro-magnet to operate the co-operative element, means operable by the key levers to set up a condition affecting the electro-magnet for operation, means operable by said actuator to effect the operation of the electro-magnet while the operable means is in its active position, a normally closed switch electrically connected with the electro-magnet, manual means operable by the key levers during the active stroke of the co-operative element to initiate the operation of said switch, automatic means effective subsequent to the actuation of the manual means to complete the actuation of said switch to open it after the printing operation of the co-operative element to render the electro-magnet ineffective, and means to return said co-operative element.

6. In a typewriting machine, the combination of printing instrumentalities including a type carrier, and a co-operative element, means including key levers to actuate the type carrier, indexing devices settable by the key levers to locate the type carrier with respect to the co-operating element, operating means to actuate one of said elements to print against the other, means settable by the key levers to condition the operating

means for subsequent actuation, and means associated with the locating means to effect the actuation of the operating means while the conditioning means is in its set position.

5 7. In a typewriting machine, the combination of printing instrumentalities including a type carrier and a co-operative element, means including key levers to actuate the type carrier, indexing devices operable by the key levers to locate

10 the type carrier with respect to the co-operating element, operating means to actuate one of said elements to print against the other, means settable by the key levers to condition the operating means for subsequent actuation, means associated

15 with the locating means to effect the actuation of the operating means while the conditioning means is in its set position, and means whereby said operating means is rendered ineffective after printing in case the settable means is still in its

20 set position.

8. In a typewriting machine, the combination of printing instrumentalities including a type carrier and a cooperative element, key-levers, means including a lever operable by said key

25 levers in opposite directions from a normal position to actuate the type carrier, means to locate the type carrier with respect to the co-operating element, an electric device to actuate one of said elements to print against the other, a carriage,

30 escapement mechanism for said carriage, means operable by the key-levers to actuate said escapement, a switch operable by the escapement to close said switch to thus establish a condition affecting the electric device for subsequent operation thereof, and a switch associated with the

35 locating means to effect the actuation of the electric device while the first mentioned switch is closed.

9. In a typewriting machine, the combination of printing instrumentalities including a type carrier and a co-operative element, means including a lever operable in opposite directions from a normal position to actuate the type carrier, means to locate the type carrier with respect

45 to the co-operating element, an electric device to actuate one of said elements to print against the other, a carriage, escapement mechanism for said carriage, key-levers, means operable by the key-

50 levers to actuate said escapement, a switch operable by the operable means upon the operation of the latter by any one of the key levers to establish a condition to permit future operation of the electric device, a second switch co-operating with the locating means to effect the actuation of the

55 electric device while the first mentioned switch is closed, and a third switch which is connected with the escapement mechanism and is operable thereby to open said third switch to render the electric device ineffective to permit the return

60 of the actuated printing element while the other two switches are closed.

10. In a typewriting machine, the combination of a type carrier and an element to co-operate therewith to print on an interposed work sheet,

a lever to actuate said type carrier to set the selected type at the co-operative element, means to actuate said lever in opposite directions from a central position, two sets of indexing devices one at each side of the central position of said lever to arrest the latter, a single element pivoted on said lever and extending beyond both sides of said lever so as to engage the active indexing device prior to said lever and so as to be operable in opposite directions on said lever by the indexing devices of the two sets, and a spring secured to said element, two members on said lever between which the free end of the spring engages to return said element to a central position on said lever, said spring and said element being effective to 15 hasten the return of the actuating lever from its effective positions in opposite directions to its central position.

11. In a typewriting machine, the combination of printing instrumentalities including a type 20 carrier, and a co-operative element, means including a lever operable in opposite directions from a normal position to actuate the type carrier, means to be engaged by said lever to locate the type carrier with respect to the co-operative 25 element, a single device pivotally supported on said lever and co-operating with the locating means to effect the actuation of the co-operative element, said device extending beyond the side edges of said lever so as to engage the locating 30 means prior to said lever and being operable irrespective of the direction in which said lever is moved, a flat spring secured at one end to said device and effective in two directions to return said device from opposite sides to a normal position, and means on said lever to constrain the other end of said spring.

12. In a typewriting machine, the combination of a rotatable type carrier, an element to co-operate therewith to print on an interposed work 40 sheet, a flat horizontally disposed actuator for the type carrier, key levers, means operable by the key levers to operate said actuator, electric means to effect the actuation of the co-operating element, indexing devices operable by said key 45 levers to be engaged by the actuator, means to render the electric means effective, the last named means including a switch supported on the actuator, the switch comprising a fixed contact element and a pivoted contact element on said 50 actuator, a stud to secure the fixed contact to said actuator, the pivoted contact element being operable by the combined action of the actuator and the active indexing pin, a main frame, a fixed contact plate on said main frame and located 55 under said actuator, said stud of the fixed contact element extending downwardly into engagement with said plate and engaging it in any one of the various positions of the actuator, means to insulate said contact element and said stud from 60 said actuator, and means to insulate said plate from said frame.

FRANK H. TREGO.
